UNITED STATES PATENT OFFICE.

ASA L. STUMP, OF STUMPTOWN, WEST VIRGINIA.

CUT-OFF FOR OIL-TANKS.

No. 848,830.

Specification of Letters Patent.

Patented April 2, 1907.

Application filed January 13, 1906. Serial No. 295,976.

To all whom it may concern:

Be it known that I, ASA L. STUMP, a citizen of the United States of America, residing at Stumptown, in the county of Gilmer and State of West Virginia, have invented new and useful Improvements in Cut-Offs for Oil-Tanks, of which the following is a specification.

This invention relates to automatic float-valve mechanism for controlling the outlets of oil-tanks, the main object of the invention being to provide a simple and effective construction of valve device adapted when the outflowing oil falls to a prescribed level to close the outlet, so as to prevent the same from communicating with the atmosphere and permitting air to have entrance into the pipe-line and thus retarding or obstructing the flow of oil therethrough.

The invention further has for its object to provide means for locking the valve in closed position and releasing such locking means when the tank is supplied to its normal level and it is desired to reset the valve for action.

With the above and other objects in view the invention consists of the construction and combination of parts hereinafter fully described and claimed, reference being had to the accompanying drawings, in which—

Figure 1 is a sectional view of an oil-tank provided with the invention, showing the valve at the limit of its upward movement. Fig. 2 is a sectional view through the tank, discharge-pipe, and valve and showing the outlet sealed by the valve and the latter locked in closed position. Fig. 3 is a detail cross-section through the valve and discharge-pipe on the line 3-3 of Fig. 2. Fig. 4 is a perspective view of the valve and locking mechanism. Fig. 5 is a detail view of the supporting-block.

Referring now more particularly to the drawings, the numeral 1 designates an oil-tank of any preferred size and construction, and 2 an oil-discharge pipe extending horizontally into the bottom thereof and closed at its inner end by a cap 3 and having at some suitable point within the tank an outlet connection 4. The pipe is supported within the tank by a bearing-block 5, having an opening through which the pipe extends and which also serves as a support for the controlling-valve 6. The valve 6 is shown in the present instance in the form of an oblong

rectangular block of wood or other suitable material which is hinged or pivoted at its lower end, as at 7, to the block and is adapted to contact with suitable stop members 8 on the block at the limit of its upward movement, in which it assumes, as shown in Fig. 1, a position slightly inclined rearwardly from the vertical in order that it may swing freely downward by gravity when the oil in the tank lowers. The valve carries a suitably-arranged float 9 to adapt it to rise when free for movement with the oil when the tank is filled and is provided upon its rear surface with a disk or plate 10, of felt, rubber, or other suitable material, to seat upon and close the outlet 4 when the valve is in lowered position. The parts thus far described are so combined and arranged that upon the downward tilting of the valve to horizontal position, as shown in Fig. 2, the disk 10 will seal the outlet 4 just prior to the leveling of the surface of the oil with the top of the outlet, whereby communication of said outlet with the atmosphere will be prevented, so as to avoid the passage of air into the discharge-pipe and main pipe-line.

In order to hold the valve in closed position, latch or locking mechanism is provided, the same comprising a pair of jaws 11 and 12 to grip the pipe 2, which jaws are connected with weighted operating arms 13 and 14, pivotally connected with U or eye bolts 15 on the valve. In the present instance each jaw and its operating-arm is shown as being formed of a single length of wire looped at their point of intersection to pivotally engage the cooperating bolt 15, as indicated at 16, and the free ends of the jaws are bent to provide lapping portions 17 and diverging extremities 18. The arms 13 and 14 extend laterally beyond the valve and are thence bent forwardly and provided at their free ends with eyes 19 for connection with cords 20, the said cords 20 being attached to a common operating rope, chain, or cable 21, passing to the outer side of the tank over a guide sheave or pulley 22. The pivoted ends of the jaws and arms are arranged between spaced guide-plates 23, fixed to the rear side of the free end of the valve, and the jaws are limited in their opening movement by stop-pins 24, carried by said plates.

The cord or cable 21 is of sufficient length to allow the valve to have free swinging.

movement, and when the tank is full the valve stands in the open position. (Shown in Fig. 1.) As the oil discharges from the tank through the outlet 4 the valve lowers there- 5 with and before the oil falls below said outlet seals the same for the purpose described. As the valve swings to closed position the divergent ends 18 of the jaws contact with the pipe, and the jaws are thus spread apart 10 to the limit of their opening movement, whereby they are permitted to pass downward over the pipe and as soon as the valve seals the outlet to swing by gravity under the action of the arms 13 and 14 into gripping 15 engagement with the pipe, thereby locking the valve in closed position, as shown in Fig. 3, so that the valve cannot accidentally open and expose the outlet 4. When the tank is refilled, a pull upon the cord 21 will release 20 the jaws from engagement with the pipe, thus allowing the valve to swing to open position for a repetition of the operation before described.

The invention will be found of value for 25 use in connection with oil-tanks which are intermittently filled and discharged to seal the outlet and prevent the objectionable entrance of air to the pipe-line when the oil falls to its minimum level.

30 Having thus described the invention, what is claimed as new is—

1. A liquid-containing tank provided with an outlet, a valve for automatically closing the outlet when the liquid falls to a prescribed level, means for automatically locking the valve in closed position, and means uninfluenced by the liquid in the tank and adapted to be manually operated for releasing said locking means.

40 2. A liquid-containing tank provided with a discharge-pipe having an outlet, a valve operating to automatically close said outlet when the liquid therein falls to a prescribed level, means carried by the valve for engaging the pipe and locking said valve in closed position, and manually-operable means uninfluenced by the liquid in the tank for releasing said locking means.

3. A liquid-containing tank provided with 50 an outlet, a swinging float-valve therein operating to automatically close said outlet when the liquid falls to a prescribed level, means for automatically locking said valve in closed position, said means being thrown into action by the closing movement of the

valve, and manually-operable means uninfluenced by the level of the liquid for releasing said locking means.

4. A liquid-containing tank provided with a discharge-pipe having an outlet, a swinging 60 float-valve therein operating to automatically close said outlet when the liquid falls to a prescribed level, locking-jaws carried by said valve to engage the pipe and lock the valve in closed position, and manually-operable means uninfluenced by the liquid in the tank for retracting said locking-jaws.

5. A liquid-containing tank provided with a discharge-pipe having an outlet, a swinging 70 float-valve adapted to close said outlet when the liquid falls to a prescribed level, pivoted gripping-jaws carried by the valve to automatically engage the pipe and lock the valve in closed position, actuating-arms connected with the jaws, and means connected with 75 said actuating-arms whereby the jaws may be manually retracted to release them from engagement with the pipe.

6. An oil-tank provided with an outlet, a valve for automatically closing the outlet 80 when the oil falls to a prescribed level, pivoted jaws for locking the valve in closed position, gravity-controlled arms for swinging said jaws closed, and means for actuating the arms to release the jaws.

7. A liquid-containing tank provided with an outlet, a float-valve for closing the outlet when the liquid falls to a prescribed level, automatically-operating locking means for securing the valve in closed position, said 90 means being uninfluenced by the liquid in the tank, and operating means extending to the exterior of the tank, whereby said locking means may be released to permit the valve to open.

8. An oil-tank provided with a discharge-pipe having an inlet, a gravity float-valve for closing said inlet when the oil in the tank falls to a prescribed level, automatic jaws carried by the valve to grip the pipe when 100 the valve is closed, weighted arms controlling said jaws, and means for actuating said arms to release the jaws.

In testimony whereof I affix my signature in presence of two witnesses.

ASA L. STUMP.
